UNITED STATES PATENT OFFICE.

WILLIAM LICHTENBERGER, OF SAVANNA, ILLINOIS.

DESIGN FOR A PIPE-HEAD FOR CHAIN-PUMPS.

SPECIFICATION forming part of Design No. 23,740, dated October 23, 1894.

Application filed August 17, 1894. Serial No. 520,640. Term of patent 7 years.

To all whom it may concern:

Be it known that I, WILLIAM LICHTENBERGER, a citizen of the United States, residing at Savanna, in the county of Carroll and State 5 of Illinois, have invented and produced a new and original Design for Pipe-Heads for Chain-Pumps, of which the following is a specification, reference being had to the accompanying drawings, showing a part thereof.

10 In the drawings: Figure 1 is a perspective view of my head for chain-pump pipes, attached to a joint of pipe. Fig. 2 is a transverse sectional view of the head on line 2—2 Fig. 1.

15 My design is for a head or water chamber of chain-pump pipes. It consists essentially

of a hollow head A rectangular in elevation, and also in cross section; open at top, having a round opening B in one side, and a conical bottom C.

20

My design relates simply to such head, and What I claim as new is—

The design for a pipe head, as herein described and shown.

In testimony that I claim the foregoing as 25 my own I affix my signature in the presence of two witnesses.

WM. LICHTENBERGER.

In presence of—

H. C. RHODES,
J. H. WESTPHAL.
